UNITED STATES PATENT OFFICE

2,547,646

MINING MACHINE CONTROL VALVE

Arthur L. Lee, Upper Arlington, Ohio, assignor to
The Jeffrey Manufacturing Company, a corpora-
tion of Ohio

Application June 12, 1946, Serial No. 676,200,
which is a division of application Serial No.
586,979, April 6, 1945. Divided and this appli-
cation October 1, 1948, Serial No. 52,234

11 Claims. (Cl. 60—97)

1

This invention relates to a mining machine and in the specific embodiment thereof disclosed in detail and in its most specific aspect it relates to a mining machine of the shortwall type. It is to be understood, however, that a great many of the features, aspects, combinations and sub-combinations are applicable to different types of mining machines including, by way of illustration but not limitation, longwall, longwall-shortwall, or arcwall mining machines.

In fact, certain features, aspects, combinations and sub-combinations are applicable to machines other than mining machines and as to them it is to be understood that they are not limited to mining machines or, if limited to mining machines, are not limited to those of the shortwall type. There are, however, other features, aspects, combinations and sub-combinations which are designed particularly for shortwall mining machines and realize their greatest, if not their only, utility in machines of this type.

An object of the invention therefore is to provide a mining machine which has a very low overall height and thus can be used to cut kerfs in very low seam coal, while at the same time providing a mining machine of this type which is very flexible in its operation.

A further object of the invention is to provide a mining machine having a torque converter in which there is a control valve for controlling the discharge pressure of the hydraulic torque converter, which control valve is preferably, but not necessarily, of the balanced type.

Another object of the invention is to provide improved control means for hydraulic apparatus on a mining machine, including a pressure relief valve preferably of the balanced character for controlling a hydraulic coupling or torque converter and preferably in which there is means to control the valve by operating handles on opposite sides of the machine which are also preferably operable in the same manner to produce similar results.

A further object of the invention is to provide simple control mechanism for both a two-speed feed control mechanism and a torque converter mechanism on a mining machine, one being preferably controlled by rectilinear or reciprocatory motion, the other by rotary motion of the common control shaft, and in the more specific embodiment of the invention the control to be duplicated on opposite sides of the vehicle and also preferably providing for similar operation to produce similar results.

Another object of the invention is to provide

2

a connection between a variable relief valve for a torque converter of a mining machine and a valve which controls the feed drum clutch, so that the feed drum is connected only when the torque converter valve is adjusted from its minimum pressure position.

A further object of the invention is to provide a control mechanism for controlling two different types of valves, in which a single shaft is involved which controls one valve by rotary motion, the other by longitudinal or rectilinear motion.

A still further object of the invention is to provide a control valve assembly for a mining machine or the like in which the valve assembly is attachable to and detachable from the frame as a unit and includes a variety of valves and also preferably includes mechanical gearing which cooperates with other mechanical gearing also carried by the frame.

Still another object of the invention is to provide a mining machine which is adapted to rest on a mine floor and to be moved as a unit while cutting a kerf, in which a plurality of hydraulic jacks are provided to adjust the height of the machine as well as its inclination along right angle axes in a horizontal plane.

Other objects of the invention will appear hereinafter, the novel features and combinations being set forth in the appended claims.

30 In the accompanying drawings,

Fig. 1 is a plan view of a shortwall type machine which incorporates the features of my invention, the cutter bar being shown cut short;

Fig. 2 is a side elevational view of the machine of Fig. 1;

Fig. 3 is a sectional plan view showing various hydraulic control valves of a combination or valve assembly which is mountable as a unit on one corner of the mining machine frame;

40 Fig. 4 is a sectional view taken on the line 4—4 of Fig. 3, looking in the direction of the arrows;

Fig. 5 is an elevational view of one side of the valve block or assembly shown in Figs. 3 and 4;

Fig. 6 is a sectional view taken on the line 6—6 of Fig. 4, looking in the direction of the arrows;

Fig. 7 is a sectional elevational view taken on line 7—7 of Fig. 5, looking in the direction of the arrows;

Fig. 8 is a sectional elevational view taken on the line 8—8 of Fig. 5, looking in the direction of the arrows;

Fig. 9 is a plan view, with parts broken away, showing particularly the control mechanism for

55

the left-hand and right-hand combination valve assemblies, and showing the dual control mechanism for both valves;

Fig. 10 is a sectional view taken on the line 10—10 of Fig. 5, looking in the direction of the arrows;

Fig. 11 is a sectional view taken on the line 11—11 of Fig. 4 of the drawings;

Fig. 12 is a sectional view taken on the line 12—12 of Fig. 5 of the drawings; and

Fig. 13 is a piping diagram as well as a schematic showing of certain parts of the mining machine, including particularly the various compartments and valve assemblies thereof.

This application is a division of my application Serial No. 676,200, filed June 12, 1946, for a Mining Machine, the latter being a division of my application Serial No. 586,979, filed April 6, 1945, for a Mining Machine.

As previously pointed out, in its most specific aspect the invention here involved relates to a mining machine of the shortwall type and many of the features, combinations, sub-combinations and aspects are limited to this type of mining machine, while a great many others are useful in other mining machines, such as longwall, shortwall-longwall and arcwall type machines, while even others find use in machines other than mining machines. With this in mind, it is to be understood that the invention of each claim is to be limited only by the terms thereof.

Referring particularly to the drawings and to the shortwall machine which is therein disclosed and in which there is incorporated the various combinations, sub-combinations, features and aspects of my invention, it may be pointed out first that one of the important considerations which dictates some of the structures is the overall height of the mining machine. This mining machine is of the type which is adapted to rest on and slide over the mine floor as a unit while cutting a kerf or, in other words, is of the well known shortwall type. As a consequence, it is desirable to make its overall height a minimum, to the end that it may be used in very low seam mines.

Referring first to Figs. 1 and 2 of the drawings, the machine includes a main frame 40 which in practice is preferably formed of two substantially independent frames including a forward motor frame or section 41 and a rearward machinery frame or section 42, the two frames or sections 41 and 42 being removably connected together as by machine screws or bolts. Removably attached to the rear end of the machinery frame or section 42 is a gummer or cuttings removing mechanism 43 which is optionally employed or omitted.

Extending forwardly from the motor frame or section 41 is a kerf-cutting mechanism 44 including an elongated cutter bar 45 which is of substantially standard construction, except for certain differences pointed out in the parent case and not here important, upon which there is mounted an endless cutter chain 46 provided with removable and reversible cutter bits 47. As is well known, the shortwall type of mining machine is adapted to be fed as a unit over the mine floor while cutting a kerf, the kerf being cut by first summing the cutter bar into the solid coal and then feeding the machine laterally or across the coal face, all the while the kerf cutting mechanism 44 is in operation.

To effect the feeding of the mining machine as a unit, both at a kerf cutting speed and at

a handling or higher speed and in reverse directions, the machine includes a pair of feed cable or rope drums 48 and 49 mounted on horizontal axes which are preferably in alignment, one on one side of the machine, the other on the other, as clearly illustrated in Fig. 1 of the drawings.

It may also be noted that the overall height of vertical dimension of the mining machine is substantially equal to the diameter of drum 48 or 49 and the top of the drum 48 or 49 is substantially at the top of said frame 40.

Drums 48 and 49 are provided with feed ropes or cables 50 and 51, respectively, which are adapted to be reeved about the sheaves of similar right and left hand rear sheave assemblies 52 and 53, respectively, and/or similar right and left hand front sheave assemblies 54 and 55, respectively.

For the present it need only be pointed out that the driving motor which drives the drums 48 and 49 tends to drive them always in the same direction, regardless of the direction of rotation of the motor, and that direction is such that it tends always to wind or pull in said ropes 50 and 51. That is, drum 48 tends always to be rotated by its driving motor in a clockwise direction, as viewed by a person facing it, and drum 49 tends always to rotate in a counter-clockwise direction, as viewed by a person facing it.

As further pointed out in the parent case, the mining machine may cut coal by being fed laterally in reverse directions and to do this, slippage is provided on one of the drums 48 or 49, as the case may be, and it is allowed to pay out with a variable pull on the associated rope, as determined by the control of the associated torque converter. In Fig. 1 of the drawings the machine is illustrated with the ropes 50 and 51 reeved about the pulleys 52 and 53 to effect a lateral feeding of the machine to the left, as viewed from the rear thereof, or upward, as viewed from the drawings.

By the mere expedient of reeving rope 50 about the sheave of front assembly 54 and reeving rope 51 about the sheave of sheave assembly 53 and making the necessary operating adjustments on the machine, it may be fed to the right, reversely of that illustrated in said Fig. 1 of the drawings.

By extending both of the feed ropes 50 and 51 directly forwardly and to mine jacks, the machine may be fed forwardly and sumped into the solid coal. By extending the rope 50 rearwardly and around an auxiliary sheave 56, then laterally to a central sheave not illustrated but which is common on machines of this type, the machine can be pulled rearwardly away from the mine face and may be loaded onto a truck in a manner well understood in the operation of shortwall machines.

The shortwall mining machine illustrated is, of course, adapted to rest on and slide over the mine floor when in operation and the supporting surfaces of the machine are provided largely by four spaced hydraulic piston jacks or motors (when employed), those at the rear being designated 57 and those at the front being designated 58. These hydraulic jacks provide for adjusting the elevation of the cutter mechanism 44 or, in other words, the effective height of the machine and also provide for adjusting the inclination or tilt thereof on right angularly related axes relative to a horizontal plane.

Attention is now directed particularly to

Figs. 3 to 12, inclusive, of the drawings, and to the structure of various valves and control or actuating mechanism therefor. It may first be noted that there are two similar combination valve assemblies which are of reverse construction, however, and which are adapted to be mounted on and demounted from the opposite rear corners of the section 42. These valve assemblies are designated 313 and 314, respectively, and their positions on the mining machine are illustrated best in Figs. 1 and 2 of the drawings. Except for the fact that one of them is a right hand device and the other a left hand device they are of substantially the same construction and a detailed description of valve 313 will suffice for an understanding of the structure of both.

Said valve assembly 313 includes a main body, block or casing 315 and removable caps or heads 316 and 317 at opposite ends thereof. Located substantially at the center of the main body 315 and extending into both the caps or heads 316 and 317 is a cylindrical bore or opening 318 which is the main cylinder of a balanced adjustable pressure relief valve which variably controls the slip and thus adjusts the torque of a torque converter or, in other words, controls the pull in pounds on one of the feed ropes 50 or 51, there, of course, being an individual torque converter and an individual control valve for each drum 48 and 49 and associated feed rope 50 and 51. The drive between the motor and each drum 48, 49 including individual torque converter is disclosed and claimed in application Serial No. 676,200.

Stated another way, this control valve controls the pressure, and thus the torque, at which there is relative rotation between the major elements of the torque converter with a consequent flow of oil through hereinafter described valve 331, 332. The volume of said oil will be directly proportional to said slip, with zero volume at no slip or direct driving.

Within the cylinder 318 is a helical spring 319, one end of which abuts a piston 320. At the other end and slidably in the cylinder 318 is a hollow sleeve 321 which is manually adjustable, as hereinafter described, to compress the spring 319.

As illustrated in Figs. 3 and 6 of the drawings, when the sleeve 321 is moved to one extreme position, which is the zero pressure position, it will move out of contact with the adjacent end of the spring 319. As the sleeve 321 is moved downwardly, as viewed in Fig. 3, or to the left, as viewed in Fig. 6, or, in other words, toward the piston 320, it will travel a small predetermined distance before contacting the spring 319 and further continuous movement thereof will compress the spring 319 and thus build up progressively the force exerted by the spring on said sleeve 321. This force is balanced by hydraulic fluid pressure so the sleeve 321 will remain at any adjusted position.

The head 316 is provided with an integral cylinder 322 which extends into the cylinder 318 and along the axis thereof and which on its outer cylindrical surface slidably receives a sleeve 323 having an integral head 324 and a flanged base 325, which flanged base overlaps a flange on the sleeve 321 so that any force transmitted to the head 324 will be delivered by the sleeve 323 through the flanged base 325 to the sleeve 321. Within the cylinder 322 is an elongated piston 326 adapted to push on the head 324.

As best seen in Fig. 6 of the drawings, the main casting 315 is provided with a hydraulic fluid inlet chamber 327 provided with an appropriate sealing ring 328 which will effect a seal 5 with the flat plate of the frame 42 to which the block 315 is removably attached as a unit with four through bolts which extend through four spaced holes 329 (see Fig. 5). It may be stated that this manner of providing connections between the large number of bores or passageways in the block or casing 315 is uniformly followed, thus providing for ready attachment or detachment of the combination valve assembly 313 and insuring a leak proof connection with associated 10 conduits.

Hydraulic fluid received in the inlet chamber 327 passes by way of bores or passageways 330 in the block 315 and head 316 to the interior of cylinder 322, thus tending to move the piston 326 in 20 a direction to compress the spring 319. This hydraulic fluid actually produces a balancing pressure to hold the sleeve 321 at any adjusted position, the result of which is to maintain the hydraulic fluid discharge from the associated torque 25 converter 234 at a predetermined pressure which may be adjusted at any value from zero to the maximum selected value, by the manual control means for sleeve 321.

Hydraulic fluid under pressure delivered to the 30 chamber 327 is also delivered to a pressure relief valve including a seal ring 331 (see Fig. 6) and a poppet 332 having a pair of integral spaced guide pistons 333 adapted to slide in a cylinder or bore 334 in the block 315. Bore 334 is open at its bottom, as seen in Fig. 4, and communicates with an open chamber 339 (see Figs. 3 and 4), which chamber 339 communicates with the interior of cylinder 318 and with a large hole or opening 340 in the back upright plate of the frame 42, as clearly illustrated in Fig. 3 of the drawings, whereby the oil discharged through the high pressure relief valve 331, 332 will flow from cylinder 334 through chamber 339 and hole or opening 340 into an oil reservoir 212. It is also evident from the above that oil in the cylinder 318 is also drained to reservoir 212 by way of chamber 339 and hole 340.

The head of the left hand guide piston 333, as viewed in Fig. 6, abuts a roller 335 mounted on 50 one end of a pivoted arm 336, the other end of which arm carries a roller 337 which rides on the bottom of a groove in the piston 320, the groove being provided to receive said arm 336.

It is evident that any force developed by the 55 compression of spring 319 will be transmitted through the pivot arm 336 to the poppet 332 and consequently the pressure at which the relief valve 331, 332 opens will be determined by the position of the sleeve 321. Furthermore, the 60 sleeve 321 will be balanced in any position to which it is adjusted, by virtue of the fact that the hydraulic fluid in the chamber 327 not only acts on the poppet 332, but is delivered to the cylinder 322 and piston 326. The internal diameter of the seal ring 321 is the same size as the internal diameter of the cylinder 322 and consequently, since the hydraulic fluid operates on two similar areas in opposing directions, these forces will be balanced, thus maintaining the 65 spring 319 compressed in any position to which it is once adjusted by adjusting the sleeve 321.

The manner of adjusting the position of the 70 sleeve 321, thereby to adjust the pull which will be exerted on the rope 50 or 51, as the case may be, will now be described. Referring particu-

larly to Fig. 3 of the drawings, it will be seen that an operating shaft 338 extends through spaced oil seals, through a bore in the cap 317 and through a bore in the casing 315, and into and through the open chamber 339. This operating shaft 338 is mounted for both rotary and longitudinal, reciprocatory or axial movement, the rotary motion being employed to control variably the pressure at which the relief valve 331, 332 operates, by adjusting the sleeve 321, and the reciprocatory motion being employed to energize selectively the hydraulic motors or actuators 272 and 278 (Fig. 13) for operating a two-speed planetary transmission associated therewith, as disclosed in detail in my parent case.

The valve 313 is, of course, individual to one torque converter 234 (Fig. 13) and one planetary transmission, while the valve 314 is individual to the other torque converter and transmission. Valve assembly 313 controls the torque converter and transmission on the right hand side of the machine, as viewed from the rear in Fig. 1, which control the drum 48, and the valve 314 similarly controls the torque converter and transmission on the left hand side leading to drum 49. Valve assemblies 313 and 314 also have valves which control the clutch mechanisms of the drums 48 and 49, respectively, as described in my parent case.

Rotary motion of the operating shaft 338 may be imparted thereto by an operating knob or handle 341 and this rotary motion is transmitted to a bevel pinion 342 (see Figs. 3 and 4), which is feathered to the shaft 338, thereby providing for reciprocation of said shaft 338 with respect to said gear 342. Gear 342 meshes with a bevel pinion 343 (see Fig. 4), on the hub of which is a pinion 344, said two pinions being mounted for rotation on a shaft 345.

As best illustrated in Figs. 4 and 11 of the drawings, the pinion 344 meshes with a rack 346 formed as an integral part of the sleeve 321. It is obvious, therefore, that by rotating the shaft 338 the sleeve 321 can be adjusted longitudinally along the cylinder 318 and, as previously described, the hydraulic fluid pressure at which the associated torque converter discharges will thereby be adjusted and this hydraulic fluid will produce a balanced condition on said torque converter control valve so that the discharge pressure thereof may be maintained substantially constant at any selected value from zero to the maximum discharge pressure. This, of course, will control the pull on the associated rope, such as the rope 50, and purely by way of illustration of the possible variation of this pull, it may be from zero to 20,000 pounds when the low speed of the transmission is connected, which is the feeding speed used when the machine is cutting a kerf, or it may be from zero to 4000 pounds pull when the high speed of the transmission is connected, which is the handling speed for the machine. These illustrative rope pulls are, of course, only such and are by no means to be considered as restricting.

It may further be mentioned that when the machine is in operation and being fed to cut a kerf the adjustment of the torque converter control valve at any value will operate to maintain a substantially constant pull on the feed rope and, consequently, the speed at which the machine will be fed will be determined by the hardness of the cutting. For example, should the coal be soft or easy to cut, the machine will cut rapidly. Where difficult cutting is encountered, the

machine will automatically compensate for the increased hardness of cutting, and feed through the coal at a slower rate.

It is to be particularly noted that this automatic control is responsive directly to the torque of the feed mechanism or, otherwise expressed, on the pull on the feed rope. Thus there is no time lag which need be overcome as is the case in those devices which attempt to control feeding speed by release responsive to overloading of the feeding or cutting motor. Experience indicates that this directly responsive type of feed control is much more satisfactory than other known types and eliminates all tendency for chattering, bucking and the like.

As previously mentioned, the shaft 338 is also employed to control the transmission. This is accomplished by a single control valve operated by longitudinal, rectilinear or reciprocatory motion of the shaft 338. Said control valve includes a bore or cylinder 347 provided in the casing 315 (see Fig. 3) into which a spool 348 reciprocates, said spool 348 being attached to or formed as an integral part of the shaft 338. Spool 348 includes a pair of spaced lands 349 and 350.

Adjacent its periphery the cylinder or bore 347 is provided with three circumferential chambers 351, 352 and 353. The chamber 351 is connected by an appropriate conduit 354 to the slow band actuator or motor 272 of the associated planetary transmission (see Fig. 13). The chamber 352 is connected with a high pressure output pipe or conduit 355 (see Fig. 13) of the high pressure pump 221 over a path which includes a number of bores in the casing 315, which path will be described hereinafter. For the time being, it may be pointed out that this path includes a bore 356 (see Figs. 3 and 8) which communicates with the bottom of the chamber 352 and which is closed by a plug, the bore 356 communicating with a longitudinally extending bore 357 (see Figs. 3, 7 and 8) formed in the casing 315. The chamber 353 communicates by a conduit 358 with the fast band actuator 278 of the associated planetary transmission.

With the spool 348 in the position illustrated in Fig. 3 of the drawings, the fast band piston motor 278 will be actuated, since hydraulic fluid under pressure in the chamber 352 will flow through the bore 347 to the conduit 358 which is in communication with said actuator or piston motor 278. Under these conditions, chamber 351 which communicates with the slow band piston motor 272 will be connected to drain by way of the rear end of bore 347 which communicates, by means of a passageway 359 in the head 316, with the interior of cylinder 318 which, as previously described, is connected to an oil reservoir 212. As clearly illustrated, for example, in Figs. 3, 7 and 8 of the drawings, portions of the cylindrical periphery of the sleeve 321 are cut away to provide a free path for oil discharged from cylinder 347.

Therefore, by pulling outwardly on the handle 341 a fast speed drive will be effected from the driving motor to the drum 48. By pushing the handle 341 inwardly, the spool 348 is, of course, also moved inwardly and pressure chamber 352 is placed in communication with chamber 351 to actuate the slow speed motor or actuator 272 and to connect the high speed motor or actuator 278 to drain through the bore 347, which at its bottom, as viewed in Fig. 3, also communicates

with the interior of cylinder 318 over an obvious bore or passageway.

It is thus evident that the operating handle 341 and the shaft 338 which it controls serves a double function of controlling by different actions the pressure relief valve for the associated torque converter and the two-speed planetary transmission which is driven through said torque converter.

Attention is now directed particularly to Fig. 11 of the drawings and to additional control provided by the valve assembly 313. First of all, it may be mentioned that in association with the previously mentioned gear 344 for adjusting sleeve 321 there is provided a spring-pressed ball detent 360 which performs a double function of making a clicking noise as each tooth passes it, thereby indicating to the operator that a predetermined amount of adjustment has been effected on the sleeve 321, and also aiding to hold the said sleeve in adjusted position to prevent hunting which might be caused by vibration of the machine.

Furthermore, it may here be mentioned that the operating handle 341 and all similar operating handles are provided with a pointer or index, thus designating their positions, the pointers being best seen in Fig. 2 of the drawings. The pointers, for example, may point upwardly when the sleeve 321 is adjusted to its zero position, as illustrated in Figs. 3, 6 and 11 of the drawings.

A control valve for the clutch of the drum 48 is also provided in the valve assembly 313 and it is controlled automatically by the actuation of the sleeve 321 under the rotary control of handle 341. This control valve includes a cylindrical bore 361 (see Fig. 11) formed in the casing 315, in which a spool 362 reciprocates. Spool 362 is provided with spaced lands 363 and 364 and bore 361 is provided with spaced chambers 365 and 366. Chamber 365 communicates with the chamber of the actuating motor of the drum clutch of drum 48 over the previously mentioned conduit which is formed by interconnected bores, pipes and the like, designated by reference character 300 (see Figs. 8 and 13).

The chamber 366 communicates with the high pressure conduit 355 leading from the high pressure pump 221 over a bore in the block 315, as illustrated in Fig. 7 of the drawings. This chamber 366 also communicates over a plugged bore in the casing 315 with the previously mentioned bore 351, by which the hydraulic fluid under pressure from pump 221 is delivered to the chamber 352 by way of bore 356. As is hereinafter pointed out more completely, there are a number of bores in the block 315 by which the hydraulic fluid under pressure delivered from the high pressure conduit 355, first to the chamber 366 and then to the bore 357, is delivered to other control valves, particularly spool slide valves which are employed to control the elevating jacks 57 and 58.

Returning now to a consideration of the structure illustrated in Fig. 11, the right hand end of the spool 362 is provided with a rigidly attached operating arm 367 which extends into the path of the sleeve 321. A helical spring 368 abuts the head 316 and extends into a recess in the spool 362, urging it to the left, as viewed in said Fig. 11.

When the sleeve 321 is adjusted to the zero torque or zero pressure position so that the torque converter will deliver substantially no torque to the drum 48, it will automatically adjust the spool 362 so as to interconnect chambers 365 and 366, thus delivering hydraulic fluid under pressure to

actuate the clutch of the drum 48 and disengage the outer member of said drum, thus providing for its relatively free rotation.

As soon as the sleeve 321 is adjusted from its zero torque or zero pressure position or during the first portion of its travel before it contacts the spring 319, the spool 362 will operate under the influence of the spring 368 to block the pressure chamber 366 and connect the drum clutch motor chamber 365 to drain by way of open chamber 339, thus draining the motor or piston actuator of the drum 48 and allowing the spring thereof to operate its clutch and effect a driving relation between the driving member and the main casting or driven portion thereof, as disclosed in detail in my parent case. Thus, drum 48 is effectively connected to the driving motor through the torque converter and the planetary transmission as an incident to building up the discharge pressure of the torque converter and it is automatically disconnected to rotate freely as an incident to the reduction of said discharge pressure to zero.

Adjacent its rear portion the combination valve assembly 313 includes three similar slide valves including spools 369, 370 and 371 (see Fig. 4), adapted to slide in cylindrical bores 372, 373 and 374, respectively, formed in the casing or block 315. The slide valve 369, 372 controls the left front jack 58, the slide valve 370, 373 controls the right front jack 58, and the slide valve 371, 374 controls the two rear jacks 57 by way of conduits 375, 376 and 377, respectively, which include a plurality of transverse and longitudinally connecting bores in the block 315, some of which are illustrated in Figs. 3, 4, 5, 7 and 8 of the drawings.

The structures of these three valves are similar and thus a description of valve 370, 373 which is disclosed in detail in Fig. 3 of the drawings will suffice for an understanding of the construction of the other two. Cylinder or bore 373 is provided with a pressure chamber 318 and, as clearly illustrated in Fig. 4 of the drawings, the three pressure chambers of these three valves are all connected by interconnecting passageways or bores and they are connected with the previously mentioned pressure passageway 351 which extends to them by longitudinal and transverse bores which may be seen by reference to Figs. 3 and 4 of the drawings. Thus, hydraulic fluid under pressure from the pump 221 is available at all times in the vertically aligned chambers of said three valves, including chamber 318 and its counterpart in each of the other two valves. Adjacent the bore 373 there is also a motor chamber 379 which communicates with the previously mentioned conduit 375 leading to the right hand front jack 58.

Adjacent the bore 373 there are also spaced drain chambers 380 and 381, both of which are connected to the interior of cylinder 318 over obvious drain bores seen in Fig. 3 of the drawings. Within the drain chamber 381 there is a spool centering spring 382 which will return the spool 370 to its center position, as illustrated in Fig. 3, whenever its projecting operating ends are released. Oil seals 383 are provided adjacent the projecting operating portions of the spool 370.

It is obvious, by reference to Fig. 3 of the drawings, that opposite ends of the spools 369, 370 and 371 extend outwardly from the casing, body or block 315 and thus may be readily operated in reverse directions by pushing on opposite ends of them.

By reference to Fig. 13 of the drawings, it will be seen that these three valves having spools 369, 370 and 371 of the two valve assemblies 313

and 314 are connected in parallel in pairs so that the operation of either spool 369 of the valve 313 or the valve 314 will control the front left hand jack 58 either to expand it or to contract it. Similarly controlling either spool 370 of valve 313 or 314 will control right hand front jack 58. Likewise, controlling the spool 371 of either valve 313 or 314 will control the two rear jacks 57.

Referring again to Fig. 3, it will be seen that the spool 370 is provided with spaced lands 385 and 386 which co-operate with the chambers 378 and 379 to control the expansion, contraction or locking of the controlled jacks.

When the parts are in their normal positions, as illustrated in Fig. 3, land 386 locks the control jack 58 in any position to which it is adjusted. If the spool 370 is moved upwardly, as viewed in Fig. 3, hydraulic fluid under pressure in chamber 378 will be communicated to chamber 379 to expand the associated jack. If the spool 370 is moved downwardly, as viewed in said figure, the motor or jack chamber 379 will communicate with the drain chamber 380 and thus permit the associated jack to contract under the weight of the mining machine.

Not only does the operator have control of one torque converter, a feed rope drum and a two-speed planetary gear by operation of a single shaft 338 and handle 341 which controls a multiple control valve 313 which is individual thereto, but dual controls are provided for each of the multiple control valves 313 and 314 whereby both of said valves may be controlled from either side of the machine and thus an operator on either side may control both torque converters, drums and transmissions.

In Fig. 9 of the drawings the structure which provides for the dual control of each valve 313 and 314 is disclosed. Some of the mechanism, including particularly that designated valve 313, is also seen in Figs. 3 and 4 of the drawings.

As previously mentioned, the shaft 338 is mounted on the casing or block 315 and thus is removable as a unit with the unitary combination valve 313. Keyed rigidly to said shaft 338 is a gear 387.

It may well be pointed out here that, seen by referring to Figs. 5 and 12 of the drawings, there is a lug or detent 388 formed on the casing or block 315 adjacent the gear 387 which is adapted to fit into a groove 389 (see Fig. 12) in the periphery of said gear 387 formed by removing one of the teeth. This detent and groove are so positioned that they are in alignment, as illustrated in Fig. 12, only when the handle 341 is rotated to its zero pressure position, or, in other words, rotated so that the parts are in the positions illustrated in Fig. 3 of the drawings.

Under these conditions, the shaft 338 and handle 341 can be reciprocated or moved rectilinearly since the detent 388 will clear the gear 387 by virtue of the groove 389. This requires the torque converter pressure relief valve to be returned to zero before it is possible to change the transmission speed. Whenever the knob or handle 341 is moved either to its full-out or full-in position, the gear will clear the detent or lug 388, for example, as illustrated in Fig. 5 of the drawings where the knob is in its full-out position which is the fast or high speed position.

Before describing in detail the complete gearing which provides for the pull control of each valve 313 and 314, it may be mentioned that this gearing is such that either operating handle will have a similar effect on its controlling valve when

rotated in the same direction or when reciprocated in the same direction. That is, handle 341 when pulled out will effect a high speed drive of drum 48. Its associated handle will do the same thing. When either of said handles is pushed in, they will effect a low speed drive of the drum 48. Likewise, rotating either of said handles in a clockwise direction will increase the rope pull on rope 50 or, in other words, increase the torque of the torque converter. The same applies for the other controls of the combination valve 314.

Mounted on an arm 390 (see Fig. 3), which is an integral part of the block 315, is a pair of wide faced meshing reach gears 391 which mesh with the gear 387 for all of its positions of adjustment produced by shifting the shaft 338, as above mentioned. The reach gears 391 reach to and drive a gear 392 rigidly attached to the end of a tubular drive shaft 393 which is mounted on spaced anti-friction bearings 394 carried in spaced partitions 213 of the two spaced oil reservoirs 212 on opposite sides of the machine.

At its right hand end, as viewed in Fig. 9, the tubular shaft 393 carries a rigidly attached shrouded gear 395 which meshes with and drives a gear 396 fixed to a longitudinally slidable shaft 397 provided with a second rigidly attached gear 398 meshing with and driving a second shrouded gear 399 which is rigidly attached to a hollow shaft 400 extending through the oil seals in a side wall of the casing 42 and provided with an operating handle or knob 401. If the knob 341 is rotated in a clockwise direction, as viewed by an operator facing it, it will drive the knob 401 in a clockwise direction, as viewed by an operator facing it, through the gears 387, 391, 392, shaft 393, gears 395, 396 and shaft 397, and gears 398 and 399.

Provision is also made so that reciprocatory or rectilinear outward and inward movement of the handle 341 and shaft 338 will produce similar outward and inward movement of the knob or handle 401 and shaft 400. To this end, also extending through the hole or opening 340, as does the arm 390, there is a pivot arm 402 removably attached to the block 315, (see Fig. 5), upon which a bifurcated double ended pivoted shipper 403 is mounted for pivotal movement about an upright pivot pin 404. The double ended shipper 403 co-operates with grooved collars formed integral with the gears 387 and 393 so that when gear 387 is moved inwardly, gear 392 and with it shaft 393 will move outwardly, and vice versa.

It may be mentioned here that when the combination valve 313 is removed as a unit, the shipper 403 and gears 391 will be removed with it and the co-operating bifurcated arms of the shipper 403 are engageable with and disengageable from the collar of gear 392 by the simple expedient of slipping them on and off said collar.

Rectilinear, longitudinal or reciprocatory motion thus transmitted to the hollow shaft 393 will be further transmitted by the shrouded gear 395 to reciprocate shaft 397 and its two gears 396 and 398, the latter of which will in turn transmit this motion to the shrouded gear 399 and its attached hollow shaft 400 and handle 401. The shipper 403 will, of course, reverse the movement of the shaft 338, as compared with the shaft 393 and thus when handle 341 is moved inwardly, handle 401 will be moved inwardly, or conversely, if handle 401 is moved inwardly it will have the same effect on the spool 348 as will the inward movement of shaft 338, and vice versa.

Control mechanism is also provided whereby similar and dual control of the torque converter valve and the transmission valve of the combination valve assembly 314 may be effected by a pair of control knobs or handles 405 and 406 on opposite sides of the mining machine. It is to be understood that operation of either of the knobs or handles 405 or 406 will produce the same operation in the valve 314 as is produced by a similar operation of either the knobs 341 or 401 in the valve 313.

Knob or handle 405 is rigidly connected to a shaft 407 extending through oil seals in the outer wall of the frame 42, which shaft 407 also extends through the hollow operating shaft 393. At its right hand end, as viewed in Fig. 9, shaft 407 extends loosely into a bore in the shaft 408 and is free to reciprocate therein. Rigidly attached to the shaft 407 between the two shrouded gears 395 and 399 is a gear 408 which meshes with a pair of reach gears 409 mounted on an arm 410 similar to the arm 390. The reach gears 409 drive a gear, not shown, but similar to the gear 387 of valve 313 and which is mounted on a shaft 411 of said valve 314 which is a duplicate in structure and function of the previously described shaft 338 of valve 313.

A pivoted shipper 412 mounted on an arm 413 similar to arm 402, co-operates with the grooved collar on the mentioned gear which is carried on shaft 411 similar to the manner in which shipper 403 co-operates with the grooved collar on gear 387. The outer end of the shipper 412 likewise co-operates with the grooved collar on the gear 408 so that rectilinear or reciprocating motion of the shaft 411 or handle 406 is transmitted to the shaft 407 and the handle 405, or vice versa. Here also, outward or inward movement of either handle 405 or 406 will produce similar motion of the other and clockwise or counterclockwise motion of either handle 405 or 406 will produce similar movement of the other.

Attention is now directed to Fig. 13 of the drawings and to certain features of the hydraulic system which have not heretofore been particularly described. A low pressure high volume sump pump 222 is effective to keep the oil in the central cell of machinery compartment 42 at a low level since it is of high capacity. This oil is then delivered over the parallel paths to the two oil reservoirs 212 at the sides of the machinery compartment by way of output conduit 414.

The output of conduit 355 of the high pressure pump 221 flows first through a high pressure relief valve 415 and whenever the fluid output of the pump 221 exceeds the fluid demand, which will be the situation during an appreciable portion of the normal operation of the machine, the relief valve 415 will open and its output delivered to various places to lubricate gears, bearings and the like.

It is thus to be noted that a pressure rather than a splash lubricating system is provided for various gears, bearings, etc., of the machine, and this is particularly desirable since it avoids the tendency which is present in splash systems for oil to leak into the motor casing or housing and damage the electrical parts of the electric driving motor. In other words, the portion of the machinery compartment 42, which communicates through any opening with the motor compartment, is not filled or even partially filled with oil, but the parts therein are lubricated by a forced feed lubricating system. The two torque converters 234 are mounted in the individual reser-

voirs 212 on opposite sides of the machine and these reservoirs will be kept full of oil at all times by the sump pump 222.

Each torque converter is, of course, controlled by its own individual variable pressure relief valve and the amount of slippage, and consequently the amount of torque developed on each drum, is dependent upon the fluid flow therefrom, as controlled by its pressure relief valve. For example, if the fluid flow from the torque converter is zero, there will be no slip whatever between the driving and driven elements thereof, and it will be in effect a direct coupling. The maximum fluid flow will develop for any given rotor speed when the casing is stationary, or, in other words, when the torque is zero, and consequently there is no rotation whatever of the associated drum 48 or 49.

It is thus evident that by the simple expedient of controlling the pressure at which the hydraulic fluid is discharged from the torque converter, the torque output thereof, or, in other words, the pull on the rope 50 or 51 of the associated drum 48 or 49, may be determined at any one of a plurality of values having an infinite number of steps.

From the above description, it is evident that the disclosed machine is of low overall height and thus meets requirements of thin seam mining. Furthermore, the machine is one which meets the requirements of conveyor mining, particularly wherein a face conveyor is employed directly behind the mining machine. The controls for the machine are located on the sides and are substantially duplicated on each side. The location of the controls at the sides is also desirable, particularly where the gummer or cuttings remover is attached and this device may either be attached or detached, or, in other words, the machine may be built with or without it and if built with it, it may be subsequently removed.

The feed rope drums on opposite sides are both power driven, each having a two-speed control and each provided with individually controllable hydraulic coupling or a torque converter in which the torque may be adjusted continuously from zero to maximum value. The high speed, of course, is primarily for handling, the low speed for feeding or cutting.

When the machine is dumped forwardly into the coal by making a sumping cut, both feed drums will be operated at their low or feeding speed and both ropes will be wound in, in this feeding operation.

When the mining machine is employed to cut a kerf by moving it across the room face, it is, of course, obvious that one of the ropes is a feed rope and is being pulled in by the feed drum which is being driven at a low speed, while the other rope is a tail rope and is being payed out under tension. This is effected in a very efficient manner by the operation of the two independent torque converters. The torque converter which controls the power or feed drum will be operated to deliver considerable torque. For example, assuming the machine being fed, as illustrated in Fig. 1 of the drawings; the cable 51 is the power cable and its drum 49 will be winding it in and feeding the machine to the left, as viewed from the rear, all the while it is cutting a kerf.

This will mean that there will be a predetermined relatively high pull on the rope 51 which may be set at any value up to 40,000 pounds. As a consequence, the torque converter controlled by the high pressure adjustable valve of the valve

assembly 314 will be operating at a relatively high pressure and low volume. In other words, it will have a small amount of slip and its hydraulic output will be discharged at a relatively high pressure.

The pull on the rope 51 will be substantially constant, as determined by the setting of the control valve which may be controlled either by handle 341 or handle 401. The rope 50, however, will be paying out and consequently the drum 48 will be operating in the reverse direction to which it tends to be driven by the primary electric driving motor, not shown. This reverse travel of the drum 48 will, of course, produce a high relative speed between the casing and the rotor of the torque converter associated with drum 48. The transmission mechanism associated therewith will be in high speed so that the reverse gear ratio will be a minimum.

The control valve for the torque converter associated with the drum 48 will be set for a very low discharge pressure and such as will permit this essentially reverse travel of the drum 48 which will cause a high fluid output of the said associated torque converter. Thus the torque converter can be controlled so that the power on its output shaft is actually greater than the power on its input shaft, with a consequent high volume of fluid delivery. In this manner the pull on the rope 50 may be adjusted at any desired value necessary to keep the cutter bar 45 in proper position as the machine is fed across the face.

It is further obvious that a reverse action will take place when the mining machine is fed in reverse direction, in which case the rope 50 will, of course, be reeved forwardly about the front sheave 187, while the rope 51 will extend rearwardly and laterally from the sheave assembly 53.

It may further be mentioned again that once the machine is placed in operation the speed of cutting will automatically increase or decrease as required by the hardness of the cutting, to maintain a substantially constant pull on the feed rope.

The hydraulic jacks 57 and 58 are also optional and, if omitted, their control valves are also preferably omitted. When provided, they may be employed to elevate the mining machine and the cutter bar 45 or to tilt it along longitudinal and/or transverse axes. This is provided by virtue of the independent adjustment of each of the front jacks 58 and the parallel or simultaneous adjustment of the two rear jacks 57 which, due to their parallel relation, provide what is in effect a three-point suspension for the mining machine when elevated by operating the four jacks.

Other features and characteristics of the mining machine are believed adequately described and explained above.

Obviously those skilled in the art may make various changes in the details and arrangement of parts without departing from the spirit and scope of the invention as defined by the claims hereto appended, and I therefore wish not to be restricted to the precise construction herein disclosed.

Having thus described and shown an embodiment of my invention, what I desire to secure by Letters Patent of the United States is:

1. Hydraulic control mechanism including a spool type hydraulic valve having a longitudinally shiftable spool operable to control a flow

of hydraulic fluid, a control shaft connected to said spool having an operator's handle shiftable rectilinearly to operate said valve to control said hydraulic fluid flow, a balanced variable pressure relief valve operable to control the pressure of the hydraulic fluid controlled by said spool valve, and means operated by rotation of said shaft and operator's handle to adjust the balanced pressure of said relief valve.

2. Hydraulic control mechanism including a spool type hydraulic valve having a longitudinally shiftable spool operable to control a flow of hydraulic fluid, a control shaft connected to said spool having an operator's handle shiftable rectilinearly to operate said valve operable to control the pressure of the hydraulic fluid controlled by said spool valve, a variable pressure relief valve, and means operated by rotation of said shaft and operator's handle to adjust the pressure of said relief valve.

3. A mining machine including a pair of control devices, operating means for said control devices including a shaft mounted for both rectilinear and rotary motion, and means interconnecting said shaft to operate one of said control devices by rectilinear motion and to operate the other of said control devices by rotary motion, said operating means further including rotary operating handles on opposite sides of said machine and mechanism whereby clockwise rotation of either handle will produce similar operation of the device controlled by said rotation.

4. A mining machine including a pair of control devices, operating means for said control devices including a shaft mounted for both rectilinear and rotary motion, and means interconnecting said shaft to operate one of said control devices by rectilinear motion and to operate the other of said control devices by rotary motion, said operating means further including operating handles on opposite sides of said machine and mechanism whereby outward rectilinear movement of either handle will produce similar operation of the device controlled by said movement.

5. A control valve assembly for a mining machine or the like including a main casing, a pressure relief valve therein, adjustable spring mechanism for varying the relief pressure of said valve, a control valve, an operating shaft connected to operate said control valve when moved rectilinearly, gear means interconnecting said operating shaft to adjust said spring mechanism when said shaft is rotated, and a second control valve operated by adjustment of said spring mechanism.

6. A control valve assembly for a mining machine or the like including a main casing, a pressure relief valve therein, adjustable spring mechanism for varying the relief pressure of said valve, a control valve, an operating shaft connected to operate said control valve when moved rectilinearly, and gear means interconnecting said operating shaft to adjust said spring mechanism when said shaft is rotated.

7. In a mining machine, a frame, a valve assembly removable from said frame as a unit, said frame and valve assembly having co-operating fluid conduits when assembled, said valve assembly including an adjustable pressure relief valve, a control valve, a common operating mechanism for said relief valve and control valve operable in different ways to control them selectively, said common operating mechanism including a shaft mounted for both rotation and reciprocation, gearing interconnecting said shaft

to operate one of said valves reversely when reversely rotated, and means connecting said shaft to the other of said valves to operate it reversely when reversely reciprocated.

8. In a mining machine, a frame, a valve assembly removable from said frame as a unit, said frame and valve assembly having co-operating fluid conduits when assembled, said valve assembly including an adjustable pressure relief valve, a control valve, a common operating mechanism for said relief valve and control valve operable in different ways to control them selectively, and means for controlling said common operating mechanisms from different positions including spur gearing part of which is mounted on said valve assembly and part on said frame.

9. A machine including a frame, a reciprocable control valve on said frame, valve operating mechanism including a pair of operating handles, one on each of two sides of said frame, both operable to produce the same action of said control valve by operating them the same way regardless of which handle is operated, said valve operating mechanism including a pair of reciprocable valve operating members, one connected to each of said operating handles, and a pivoted member pivotally connecting said valve operating members whereby they move in reverse directions when either of said operating handles is operated.

10. A machine including a frame, a rotary control valve on said frame, valve operating mechanism including a pair of operating handles, one on each of two sides of said frame, both operable to produce the same action of said control valve by operating them the same way regardless of which handle is operated, said valve operating mechanism including a pair of rotary valve operating members, one connected to each of said operating handles, and spur gearing connecting said valve operating members whereby

- they rotate in reverse directions when either of said operating handles is operated.
11. A machine including a frame, a reciprocable control valve on said frame, a rotary control valve on said frame, valve operating mechanism for operating both of said valves including a pair of operating handles, one on each of two sides of said frame, both operable to produce the same action of said control valves by operating them the same way regardless of which handle is operated, said valve operating mechanism including a pair of reciprocable and rotatable valve operating members, one connected to each of said operating handles, a pivoted member pivotally connecting said valve operating members whereby they move in reverse rectilinear directions when either of said operating handles is moved rectilinearly, and gearing connecting said valve operating members whereby they rotate in reverse directions when either of said operating handles is rotated.

ARTHUR L. LEE.
